OF SAME PLACE.

DESIGN FOR A SPOON, FORK, &c.

SPECIFICATION forming part of Design No. 20,843, dated June 16, 1891.

Application filed May 8, 1891. Serial No. 392,105. Term of patent 3½ years.

To all whom it may concern:

Be it known that I, HENRY GREEN PEIRSONS, a citizen of the United States, residing at the city of Troy, in the county of Rensselaer and State of New York, have invented and produced a new and original Design for Handles for Spoons, Forks, &c., of which the following is a specification, reference being had to the accompanying drawing, representing a spoon or fork having my said new design.

My design consists, essentially, of the scenic representation on the face of the broad upper portion of the handle of a mountain *a*, with foot-hills *b*, and in the foreground ruins *c*, and

lower on the handle a representation of the head and shoulders *d* of an officer in a uniform of the American Revolution, substantially as shown in said drawing.

What I claim is—

The design for a handle for a spoon or fork herein shown and described.

In testimony whereof I hereunto set my hand, in the presence of two subscribing witnesses, this 6th day of May, 1891.

HENRY G. PEIRSONS.
